UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

KEY-LEVER TENSION DEVICE.

1,375,789.

Specification of Letters Patent. Patented Apr. 26, 1921.

Application filed June 3, 1918. Serial No. 237,934.

To all whom it may concern:

Be it known that I, OTTO A. HOKANSON, a citizen of the United States, residing at Woodstock, in the county of McHenry and State of Illinois, have invented certain new and useful Improvements in Key-Lever Tension Devices, of which the following is a specification.

This invention relates to typewriters, and 10 more particularly to the means for varying the tension which is placed upon the key levers of a typewriter.

The principal object of the invention is to provide a new and improved construction by 15 means of which the spring pressure which opposes the movement of the typewriter key levers can be varied to meet various conditions of touch and operation, to quicken the return of the type bars, and prevent 20 them from colliding.

The invention consists in the novel construction, combination and arrangement of the parts.

In the accompanying drawings—

25 Figure 1 is a side elevation with parts shown in section of a key lever tensioning device constructed in accordance with the principles of this invention.

Fig. 2 is a view of the under side of a 30 machine showing a portion of the mechanism.

Fig. 3 illustrates a modified form;

Fig. 4 is a view from the under side of a 35 machine embodying the modified form; and

Fig. 5 is a detail of an eccentric adjusting screw.

Figs. 6 and 7 are fragmentary views similar to the parts of Figs. 1 and 3, respectively, 40 showing a slight modification of the invention.

It is frequently necessary to vary the tension applied to the key levers of a typewriter, and although each key lever usually 45 has separate means for varying the tension of the spring which returns the key lever, it is also desirable that additional means be provided for changing the tension of all of the key levers for different conditions in 50 writing, and to accommodate the touch of different typewriter operators. The individual adjustment of the key lever tension mechanism is usually made at the factory for the purpose of equalizing the actions 55 or the several key levers, but it is found in

practice that it is necessary to provide an additional tensioning means which can be easily applied by any operator so that the machine will be satisfactory for that individual's touch. The present invention 60 relates to the provision of such an additional tensioning device as applied to a typewriter.

At the rear of a typewriter frame 1 is a sub-frame or support 2, which has an upright slotted projection 3, with a rearwardly opening groove 4, in which a pivot wire 5 is seated. A plurality of key levers 6 are mounted in the slots and have an upright groove 7 at their rear ends for pivotally mounting the key lever on the pivot 65 wire. An angular plate 8 is secured to the under side of the sub-frame 2 and has an edge which extends just below the pivoted ends of the key levers to prevent them from being accidentally displaced from their pivotal mounting. The lower edge of each key lever is formed with a projection 9 which seats one end of a coil spring 10, the other end of which engages a variable tensioning screw 11 threaded into the under side of 80 the sub-frame 2, the spring tending to press the front end of the key lever upwardly. Near the front end of the key lever a transverse slotted comb 12 is secured to the frame for guiding this end of the key levers, and 85 intermediate the ends of each key lever it is provided with a pin 13 which engages a slot in a pivoted type bar actuating lever 14 which is actuated in the well-known manner by the depression of the key lever. 90

Also mounted upon the pivot wire 5, at each end thereof, is an arm 15 which supports a universal bar 16 formed with separate tongues 17, each of which is adapted to be engaged by the lower edge of a key lever 6 in its downward movement, the tongues being bendable so that the engagement of the key levers therewith can be varied to a certain extent to make up for variations in size and shape of the different 95 parts. Attached to the outer side of the universal bar, adjacent the center thereof, is a bracket 18 to which a link 19 is pivotally connected for operating the ribbon vibrator, escapement and other mechanisms of the 100 typewriter. This link is held upwardly by the parts to which it is connected (not shown), and in normal position, the universal bar lies just below the edges of the key levers so that it will be engaged by the actu- 105 110

ation of any one of them and move downwardly, carrying the link 19 with it.

Pivoted in a bracket 20 extending downwardly from the sub-frame 2, as shown in Figs. 1 and 2, is a shaft 21 to which forwardly extending arms 22 are secured adjacent the end thereof, and a rearwardly extending arm 23 adjacent the center thereof. The forwardly extending arms 22 project just below the universal bar 16 which is provided with contact buttons 24 which are adapted to be engaged by the extremities of the arms 22 when the universal bar is moved downwardly a predetermined amount by the engagement of the key levers. The rearwardly extending arm 23 has a bent extremity 25 which normally rests upon a stop screw 26 threaded in the typewriter frame, and the arm is yieldingly held in this position by means of a spring 27, one end of which engages the arm, and the other end of which is in engagement with an adjusting screw 28, which is threaded through the rear portion of the frame and is provided with a head for engagement by the fingers of an operator.

It will be obvious from this construction that the tension applied by the spring 27 to the arm 23 can be varied by the movement of the screw 28, thereby varying the spring tension and the amount of opposition which will be offered to the movement of the universal bar as soon as it engages the extremities of the arms 22. In order to hold the adjusting screw 28 in any position in which it is placed, a disk 29 of rubber, or the like, as shown in Fig. 3, is pressed against the adjusting screw 28 by means of a set screw 30, and in order to hold the key lever tension screws 11 in their adjusted position, a plate 31 with spring tongues 32 is held yieldingly against the screws.

In the form shown by Figs. 3, 4 and 5, the operating parts are substantially the same as shown in Fig. 1, but the universal bar 33 is mounted in arms 34 pivoted on a shaft 35 which is mounted in brackets 36.

A single bracket 37 is attached to the center of the plate 8, and in this bracket a lever 38 is pivoted which has a bent extremity 39 engaging the stop screw 26, and at its other end it has a pin and slot connection with a link 40 which is pivotally connected to one of the arms 34 which supports the universal bar 33. This lever 38 is preferably mounted in the bracket 37 by means of an eccentric screw 41 which permits the pivot point of the lever to be varied as desired.

It will be seen that the action of the two devices is substantially the same, for the lever 38 will have no effect upon the universal bar 33 until the pin and slot connection between it and the link 40 is taken up which corresponds to the movement of the

universal bar 16 until it engages the extremities of the arms 22.

It is contemplated that this construction may be used purely as an adjustable tensioning device for the key levers, and in such a case the bracket 18 would be omitted from the universal bar 33, as well as the connecting link 19, and this bar 33, as shown in Fig. 6, would then become simply a rail which would be engaged by each of the key levers upon their depression. For obtaining this result instead of the construction shown by Fig. 3, the link 40 and the lever 38 would be connected simply by a pivot pin as shown in Fig. 6 instead of a pin and slot connection so that after a predetermined downward movement of each key lever it engages the rail and the pressure of spring 27 is directly applied to oppose the further depression of the key lever, and also to return it quickly when pressure on the key lever is released. The same action would be obtained in the construction shown by Figs. 1 and 2 if the bracket 18 and the link 19 are removed from the bar 16 allowing the contact buttons 24 to rest directly upon the tips of the arms 22 as shown in Fig. 7.

I claim:

1. In a typewriter, a plurality of pivoted key levers, means tending normally to hold them resiliently in place, a universal bar directly engaged by the key lever after a predetermined movement thereof, resilient means tending to oppose the movement of the universal bar after a predetermined movement thereof and means for regulating the tension of said resilient means to control the key lever tension of said typewriter.

2. The combination with a pivoted and spring-pressed key lever, of a universal bar engaged by the key lever after a predetermined movement thereof, and resilient means comprising a spring-pressed lever with extremities spaced from the universal bar and engaged thereby upon a predetermined movement of the universal bar by the key lever.

3. The combination with a key lever, of a universal bar engaged thereby, an additional spring tension means for the universal bar comprising a lever pivoted intermediate its ends and having one end engaged by a stop in such position to hold the other end at a distance spaced from the universal bar in the path of movement thereof, and a spring tending normally to hold the lever against the said stop.

4. In a key lever tensioning device for typewriters, a universal bar engaged and moved by each of the key levers, a lever pivoted intermediate its ends having one extremity thereof resiliently held in such position that the other end thereof is normally spaced from the universal bar but is in the

path of movement thereof, and a friction button carried by the universal bar for engagement with the end of said lever.

5. The combination with a key lever and means for normally tensioning it, of a universal bar normally spaced from but engaged by the key lever in its operative movement, an adjustable spring tension device comprising a lever one extremity of which 10 is normally spaced from the universal bar but in the path of movement thereof, a spring in engagement with the other end of the lever, and an adjusting screw for varying the tension of said spring.

15. 6. The combination with a pivoted key lever and adjustable means for varying the normal tension thereof, of a universal bar engaged by the key lever in its operative movement, an additional key lever tensioning means comprising a lever in the path of movement of the universal bar but normally spaced therefrom, and means for varying the tension applied to the said lever.

7. In a key lever tensioning device, a lever 25 pivoted intermediate its ends, a stop for one end of the lever, a spring of which one end engages the lever for holding it against the stop, an adjusting screw for engaging the other end of the spring, and means for holding the adjusting screw in any set position, said means comprising a yielding disk and a set screw for pressing the disk against the threads of said adjusting screw.

8. In a typewriter, a plurality of key levers pivoted at their rear ends and each 35 having a separately adjustable spring tensioning means, a universal bar having bendable tongues each engaged by one of the key levers when the key levers are operated, an additional tensioning means for the key 40 levers comprising a lever pivoted intermediate its ends having a stop at one end for holding the other end of the lever normally at a distance from the universal bar, and adjustable spring tensioning means for holding the lever against the stop whereby a yielding opposition is offered to the movement of the universal bar when it is moved a predetermined distance by the engagement 45 of any key lever therewith.

9. In a key lever tensioning device for typewriters, a tensioning lever pivoted below the key levers, a stop for one end of the lever, a spring tending to press the lever against the stop, a member extending transversely below the key levers and adapted to be engaged by them upon a predetermined downward movement, and means forming an engaging contact between said member and the tensioning lever to aid the tension 55 of said spring in opposing the downward movement of the key levers.

In testimony whereof I have signed my name to this specification on this 29th day of May A. D. 1918.

OTTO A. HOKANSON.
